UNITED STATES PATENT OFFICE.

ALBERT F. STAPLES, OF NEW YORK, N. Y.

SHOVEL.

1,241,677.

Specification of Letters Patent.

Patented Oct. 2, 1917.

Application filed November 6, 1915. Serial No. 60,057.

To all whom it may concern:

Be it known that I, ALBERT F. STAPLES, a citizen of the United States, and resident of New York, in the county of New York and State of New York, have invented certain new and useful Improvements in Shovels, of which the following is a specification.

This invention relates more particularly to shovels of the type in which a foraminous body is employed, so that the shovel may be used as an ash-sifter.

In U. S. Letters Patent No. 1,108,270, granted to me August 25, 1914, I have disclosed a shovel designed for use as an ash-sifter, and the present invention relates to improvements in the device disclosed in that patent. One object of the invention is to improve the form and construction of the body of the shovel, in such a manner as to promote the sifting of the ashes therein, and to this end I so form the body that at its closed rear end it has a central forwardly-convex portion and lateral concave portions or pockets, the effect of this form being to cause a mass of ashes, when moving rearwardly within the body, to be divided and projected somewhat outwardly, toward the sides of the body, which facilitates the passage of the ashes through the interstices of the body.

Another object of the invention is to provide a light, rigid and inexpensive construction for the body of the shovel. To this end I form the body of a series of continuous wires, each comprising lateral, substantially straight, parallel members connected together, at their rear ends, by transverse members, these transverse members being fastened in the shank or handle of the shovel in the novel manner hereinafter described.

Another object of the invention is to improve the means for supporting the body of the shovel upon a floor or other horizontal surface, when in use, in such a manner as to facilitate both the operation of filling it with ashes, and its reciprocating movement in the operation of sifting the ashes. To this end I employ, in connection with the manually movable closure-member hereinbefore referred to, certain floor-engaging projections and runners hereinafter described.

In the accompanying drawings:—

Figure 1 is a plan-view of a shovel embodying the present invention, with a por-

tion of the handle broken away, and showing the closure-member in depressed or open position;

Fig. 2 is a side-elevation, partly in vertical section, showing the parts in the same position; and

Fig. 3 is a side-elevation of the shovel, showing the closure-member in closed position.

The invention is illustrated as embodied in a shovel having a foraminous body 5, an elongated handle 6, and a manually movable member 7 adapted to constitute, alternatively, an end-closure and a lip for the body 5.

One feature of the invention resides in the form and construction of the body 5. The body is formed by a series of continuous lengths of wire, each comprising two substantially parallel lateral members 8, connected by a transverse member at the rear. The transverse members of the wires, as shown particularly in Fig. 1, are bent so as to provide forwardly-convex middle parts 9, and lateral concave parts 10, the middle parts 9 being fixed to the shank 11 by which the body is connected with the handle 6. When the member 7 is in raised position, so as to close the opening in the body, the mass of ashes in the shovel may be shaken back and forth in the usual manner, and the finer ashes will pass through the spaces between the parallel wires of the body. When the ashes are shaken, in this manner, against the rear end of the body they are divided by the central convex part adjacent the shank 11, and are thus thrown outwardly into the concave parts 10, and more or less against the side-members 8 of the body. This action facilitates the sifting of the ashes, as it prevents them from being concentrated against the imperforate shank and increases the agitation to which they are subjected.

Another feature of the invention resides in the simple and effective means for connecting the body with the handle. For this purpose the shank 11 is channel-shaped, being made preferably of sheet-metal, and the edges of the lateral flanges of the shank are notched, as shown, to receive the middle portions of the wires. The wires are secured and clamped in the notches by means of a clamping-member 12, in the form of a strip of sheet-metal which lies across the wires and between the flanges of the shank.

Rivets 13, passing through the shank and the clamping-member, draw these parts tightly together, thus binding the wires securely in place.

5 The forward ends of the wires are connected by a sheet-metal member 14, and this member is also connected with the shank of a U-shaped strip 27, which forms the upper margin of the body. To still further 10 strengthen and stiffen the body, I employ a truss-like construction connecting the handle with the member 14. The clamping-member 12 is continued forwardly to form the middle portion of the body, and also to 15 constitute the upper truss-member, while the lower member is in the form of a metal strip 28. The rear end of the strip is secured to the handle by the same rivets 29 which secure the shank in place. The member 12 and the strip 28 are connected rigidly by the rivets 13 and by additional rivets 30, being spaced apart by sleeves 31 surrounding the rivets, as shown in Fig. 2. At their forward ends they are riveted to 25 the top and bottom of the member 14.

The member 14 is provided, at its forward edge, with sleeves to receive a hinge-pintle or pivot-wire 15, and the closure-member 7 is provided with corresponding hinge-sleeves embracing the wire 15, so as to pivot the closure-member to the body. As in the sifter-shovel of my said patent, the closure-member has lateral portions 16, bent at right-angles to its body-portion, and constituting continuations of the sides of the body when the member is in position to act as a lip for the body. These lateral members 16 are also extended rearwardly and downwardly, so as to provide supports 17 30 which project to a substantial distance beneath the body when the end-closure is in closed position, as in Fig. 3.

A feature of the invention resides in the provision, upon the forward and lower edges 45 of the supports 17, of projections or convex portions 18, which are so located that when the closure-member is in position to act as a lip, as in Fig. 2, these portions 18 project slightly below the body so that they may engage the floor-surface upon which it rests and act as runners to partially support the shovel. The pressure of these members against the floor-surface has the further useful function that it tends to cause the 50 closure-member to be swung downwardly, so as to maintain its forward edge in close engagement with the floor-surface, thus causing it to act effectively as a lip to enter beneath a mass of ashes resting on the floor, notwithstanding variations in the angle at 55 which the body is presented to the floor-surface.

The closure-member 7 is manually operated by means of a rod 19, which is pivoted, 60 at its forward end, to a lug 20 struck up

from the closure-member. The rear end of the rod is provided with a handle 21, and when the rod has been drawn rearwardly, to close the shovel, the handle 21 may be conveniently grasped together with the transverse grip 22 of the handle of the shovel, thus enabling the shovel to be operated conveniently with one hand.

In order to hold the closure-member 7 rigidly in open position, the rod 19 is provided with a collar 32 which co-operates with a slotted detent-plate 33 fixed on the side of the handle. When the rod is thrust forwardly the collar rides over the slanting surface of the detent and then snaps into engagement with its end, owing to the resiliency of the rod. When the closure-member is to be returned to closed position the operator may release the collar from the detent by bending the rod outwardly.

In the sifter-shovel described in my said patent the supports corresponding to the parts 17 of the present device are adapted to rest directly upon the floor-surface, and constitute the sole means for supporting the body from the floor. A feature of the present invention, however, resides in the use of elongated runners interposed between the supports 17 and the floor-surface. These runners, as illustrated, are formed by a single length of heavy wire comprising two substantially parallel members 23 adapted to engage the floor-surface and to move smoothly over it. The forward ends of the runners are bent upwardly, and are pivoted to the support 17 by means of rivets 24, while the rear ends of the runners are connected by a transverse curved member 25. This transverse member is connected, at its middle point, with the shank 11 by means of a U-shaped link 26, which has eyes at its ends embracing the part 25, while its transverse middle portion is loosely embraced between the shank and the clamping-member 12, as shown in Fig. 2. The parts are so proportioned and arranged that when the closure-member is in position to act as a lip, as shown in Fig. 2, the link 26 is swung to its rearmost, substantially horizontal position, and the body of the shovel may then rest directly upon the floor-surface, since the link may swing upwardly sufficiently to permit the runners to be pressed snugly up against the body.

While I have described the body of the shovel as composed of a wire fabric consisting solely of parallel wires, it will be apparent that it may be composed of foraminous wire fabric of other forms, and that, in general, my invention is not limited to the embodiment thereof hereinbefore described and illustrated in the accompanying drawings, but may be embodied in various other forms, within the nature of the invention as it is defined in the following claims.

I claim:—

1. In a shovel, the combination, with a foraminous body, of a manually operable member pivoted to the forward end of the body and movable into position to constitute, alternatively, an end-closure and a lip, said member comprising also supports movable into and out of a position in which they project to a substantial distance below the body; the supports having convex portions, on their forward edges below the pivotal axis, which project slightly below the body, in the rear of the pivotal axis, when said manually operable member is in position to 10 act as a lip, so that said convex portions are adapted to act as runners for the shovel and to maintain the lip in depressed position.
2. In a shovel, the combination, with a foraminous body and a member pivoted to the forward end of the body and manually movable into position to constitute, alternatively, an end-closure and a lip for the body, of runners extending longitudinally below the body; and means for lowering and 25 raising the runners according as the end-closure is in closed or open position.

3. In a shovel, the combination, with a foraminous body and a member pivoted to the forward end of the body and manually 30 movable into position to constitute, alternatively, an end-closure and a lip for the body, of runners extending longitudinally below the body and pivoted, at their forward ends, to said member so as to be raised 35 when said member is in open position and lowered when it is in closed position.

4. In a shovel, the combination, with a foraminous body and a member pivoted to the forward end of the body and manually 40 movable into position to constitute, alternatively, an end-closure and a lip for the body, of parallel runners extending longitudinally below the body and formed by a generally U-shaped rod having its ends 45 pivoted to said manually movable member; and a link pivoted at its ends, respectively, to the middle portion of said rod and to the body of the sifter.

5. A shovel having, in combination, a 50 shank channel-shaped in cross-section and

provided with a series of notches in the edges of its side-flanges, a series of wires bent to provide side-members substantially parallel and extending forwardly from the shank, and middle-portions seated in said 55 notches, a clamping - member extending across the middle - portions of the wires on the opposite side from the shank, and means for fixing the clamping-member to the shank so as to clamp the wires in the 60 notches.

6. In a shovel, a body having a foraminous closed rear end, comprising a central forwardly projecting portion, and two lateral concavities into which the contents of 65 the body may be deflected by the central portion.

7. In a shovel, a body comprising a series of wires, each bent to provide two substantially horizontal parallel side-members and 70 a transverse rear portion connecting the side-members, said rear portion being forwardly convex at the middle and concave at each side thereof; and a shank fixed to and connecting the wires at the middle of said 75 rear portions.

8. In a shovel, a body comprising a channel-shaped shank; a foraminous wire fabric crossing the open side of the shank and extending forwardly therefrom; a clamping- 80 member extending along the shank and across said wire fabric and secured to the shank to clamp the wires thereon, the clamping-member also extending forwardly from the shank; and a transverse member connecting the forward extremities of the 85 clamping-member and the wire fabric.

9. In a shovel, the combination, with a foraminous body and a member pivoted to the forward end of the body and adapted to 90 serve alternatively as a closure and a lip therefor, of manually operable means for moving the closure to, and holding it in open position, said means comprising a rod extending from the closure-member to the 95 handle, and a detent for preventing rearward movement of the rod when the closure-member is in open position.
